UNITED STATES PATENT OFFICE

157,272

TOILET SEAT HINGE

Robert H. Lillyblad and Jacob A. Broersma, Grand Haven, Mich., assignors to American Brass Novelty Company, Grand Haven, Mich., a corporation of Michigan

Application June 28, 1948, Serial No. 147,246

Term of patent 14 years

(Cl. D4—5)

To all whom it may concern:

Be it known that we, Robert H. Lillyblad and Jacob A. Broersma, citizens of the United States, residing at Grand Haven, in the county of Ottawa and State of Michigan, have invented a new, original, and ornamental Design for Toilet Seat Hinge, of which the following is a specification, reference being had to the accompanying drawing, forming part thereof.

Fig. 1 is a plan view of the toilet seat hinge showing the new design.

Fig. 2 is a side elevation of the same, and

Fig. 3 is an end view of the same.

Fig. 4 is a sectional view on the line 4—4 of Fig. 2.

We claim:

The ornamental design for a toilet seat hinge, substantially as shown.

ROBERT H. LILLYBLAD.
JACOB A. BROERSMA.
